CLAIM

The ornamental design for an ultrasonic sandblasting therapy device as shown and described.

DESCRIPTION

The file of this patent contains at least one drawing/photograph executed in color. Copies of this patent with color drawing(s)/photograph(s) will be provided by the Office upon request and payment of the necessary fee.

1. Ultrasonic sandblasting therapy device
2. Ultrasonic sandblasting therapy device

- 1.1: Front
  - 1.2: Back
  - 1.3: Left
  - 1.4: Right
  - 1.5: Top
  - 1.6: Bottom
- 2.1: Front
  - 2.2: Back
  - 2.3: Left
  - 2.4: Right
  - 2.5: Top
  - 2.6: Bottom

The portion of the design shown in the color red is for the purpose of illustrating portions of the ultrasonic sandblasting therapy device that forms no part of the claimed design.
